WEFT DETECTOR SYSTEM FOR SHIFTING
BOX ENDS OF LOOMSLewis S. Vose, Worcester, Mass., assignor to
Crompton & Knowles Loom Works, Worcester,
Mass., a corporation of MassachusettsApplication May 7, 1935, Serial No. 20,117
Renewed August 4, 1936

12 Claims. (Cl. 139—233)

This invention relates to improvements in weft detecting systems for fancy or multi-shuttle looms and it is the general object of the invention to provide such a system usable more particularly on the shifting shuttle box end of the loom and effective to detect the shuttle immediately before it is picked whether previously active or inactive.

Looms of the type to which my invention more particularly relates ordinarily employ shifting shuttle boxes on at least one end of the lay, the boxes shifting while the lay is in the forward part of its sweep to render a previously inactive shuttle active. The shuttle boxes can remain at rest for an extended period during which either of the 10 shuttles remains in action. In my co-pending application Serial No. 593,814 I have shown a pair of electric weft detectors secured to the lay, one over and the other under the boxes, so related to the latter as to have detecting relation with the 20 inactive shuttle but incapable of detecting the active shuttle. In such a loom the period during which any one shuttle may remain active is necessarily limited. It is an important object of my present invention to add a third or auxiliary detector positioned and controlled to detect in the active shuttle only, thereby supplementing the other two detectors and permitting any one shuttle to remain in action as long as desired.

The third detector may conveniently be 30 mounted in front of the lay to detect the active shuttle on those forward beats of the lay when there is no shifting of the boxes. When there is to be a change in the running or weaving shuttle the boxes will shift during the time that the additional detector would ordinarily feel for the condition of weft and it is a further object of my invention to provide means for moving the additional detector out of interfering position with respect to the boxes when they shift.

The detectors secured to the lay will ordinarily 40 operate to indicate exhaustion when a depleted shuttle previously inactive is about to be returned to action by shifting of the boxes and I provide a control originating in the pattern mechanism for permitting one or the other of these detectors to communicate indication of weft exhaustion to a means for changing loom operation during those picks when the additional detector is removed from detecting position. In this way I provide for 50 detecting the condition of weft in each shuttle before it is picked irrespective of whether it was previously active or inactive. The control for the detectors may include a switch movable by the pattern mechanism or in some other way coordinated with the shifting boxes so that the detector

of the inactive shuttle will be incapable of indicating exhaustion when the third detector is positioned for a detecting operation.

Any one of a variety of mechanical devices may be employed to move the additional detector to non-detecting position, but I have shown a cam surface and actuator therefor brought into action by a part which moves in timed relation with the shifting boxes. I do not wish, however, to be limited to a cam inasmuch as this is not the only means by which the additional detector can be moved out of detecting position at the desired times.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an end elevation of the shifting box end of the loom having my invention applied thereto, certain parts being in section,

Fig. 2 is a front elevation on an enlarged scale partly in section taken in the direction of arrow 2, Fig. 1,

Fig. 3 is a front elevation taken in the direction of arrow 3, Fig. 1, showing the control for the box motion and switch, certain of the structure being in section,

Fig. 4 is a view similar to a portion of Fig. 1 with the additional detector moved out of the path of the shifting boxes and indicating diagrammatically the path traversed by the shuttles and their bobbins during shifting,

Fig. 5 is a diagrammatic view of the electric circuits indicating the form of control adaptable to a continuously running shuttle changer of a type which has gone into general use,

Fig. 6 is a fragmentary diagrammatic view indicating control means for another type of shuttle changer of well-known construction, and

Fig. 7 is a modification showing a different means for mounting the additional detector.

Referring to Figs. 1 and 2, I have provided a loom frame 10 having a lay 11 movable back and forth relatively to the front of the loom by a connector 12 driven by the top shaft 13. A lay end 14 has slidably mounted thereon a gang of boxes B comprising upper and lower cells 15 and 16, respectively, mounted on a box lifter rod 17. The lower end of the rod is connected to a yielding link 18 attached as at 19 to a box lifter lever 20. The latter may be pivoted to a fixed stud 21 and extends rearwardly to be connected to a depending

link 22. The lower end of the latter is pivoted to a disk 23, see Fig. 3, secured to a short shaft 24 driven intermittently by a pinion 25. The latter has two separated segments of gear teeth and is 5 provided with two bull teeth 26 and 27, respectively, which are displaced with respect to each other along the length of the shaft 24 so that only one tooth at a time can cooperate with a segmental master gear 28 secured to the bottom 10 shaft 29.

The bull teeth are moved by a sliding positioner 30 having a stem 31 which extends through a box motion frame 32 secured to the loom. The stem is surrounded by a compression spring 33 15 which tends normally to move the positioner to the left as viewed in Fig. 3, while a flexible connector 34 attached to the positioner as at 35 extends around a fixed sheave 36 and upwardly to be attached as at 37 to a pattern lever 38.

20 Lever 38 is movable either to high or low position by a pattern chain 39 consisting of high and low rolls 40 and 41, respectively. The chain can be built to produce any desired pattern having two different colored wefts, that is, the pattern may have a series of successive high or low rolls as indicated in the lower portion of the chain shown in Fig. 3, or the high and low rolls may alternate as shown in the upper part of the chain immediately under the pattern lever 38. 25 The pattern lever moves about a fixed pivot 42 and when rising moves the positioner 30 to the right as viewed in Fig. 3, but when falling permits the spring 33 to move the positioner to the left.

30 Box motions of the type indicated are well-known and a further description is deemed unnecessary. It is sufficient for present purposes to state that rising of the pattern lever 38 is accompanied by an upward shifting of the shuttle boxes by a force originating in the master gear 28 and transmitted through the link 22, lever 20, and box lifter rod 17. The bottom shaft has a complete revolution every second beat of the loom and the pattern chain is given an advance 35 movement also on every second beat, so that one ball of the pattern chain corresponds to two successive beats of the loom. The matter thus far described may be as commonly used in box looms.

40 As shown more particularly in Fig. 2 I provide a bracket 40 extending upwardly from the lay end 14 and having mounted thereon an electric detector 41 from which extends two electric conducting wires 42 and 43. The detector is provided with a pair of detecting fingers or prongs 44 which are adapted for engagement with the bobbins W of the shuttle S in the upper box, and contacts with a conducting surface such as a metallic ferrule in the shuttle when the weft is substantially depleted. Detector 41 is positioned to be out of detecting relation with respect to the upper cell 15 when the latter is active and the boxes are down.

45 In a similar manner I provide a second bracket 50 depending from the lay end and carrying a second electric detector 51 from which extend conducting wires 52 and 53, respectively. Detector fingers or prongs 54 extend upwardly from the detector to detect bobbin W' in shuttle S' in the lower cell 16 in a manner similar to that 50 already described in connection with the upper detector 41, and detect their corresponding shuttles only when the latter are inactive.

55 The two feelers of the detector mechanism secured to the lay have detecting relation with 75 their corresponding shuttles due to shifting of

the shuttle boxes. The detectors may if desired be similar to those shown in Payne Patent No. 1,924,197.

The detectors 41 and 51 and the manner in which they cooperate with shuttles S and S' of themselves form no part of my present invention, being similar to the corresponding parts shown in my co-pending application Serial No. 593,814.

As previously stated the detectors 41 and 51 10 operate in such a manner as to restrict the loom to the weaving of very simple patterns, such for instance, as two picks of one character of weft followed by two picks of a different character of weft. In order to render the loom capable of 15 weaving with any desired sequence of wefts of two different characters as in call box weaving I provide an additional detector mechanism to cooperate with the active shuttle which normally cannot be detected by the detectors mounted on 20 the lay.

Accordingly, as shown in the preferred form of the detector as set forth in Fig. 1, I provide a third additional detector 60 which itself is similar to the detectors already described and comprises a pair of prongs 61 which have detecting relation with the active shuttle during the forward beat of the lay on non-box-shifting picks of the loom. These prongs are electrically connected only when the prongs are electrically connected by an uncovered conducting surface in the active shuttle. As shown in Fig. 1 the detector is mounted on a slide 65 movable backwardly and forwardly in a stand 66 secured to the loom frame. A light tension spring 67 interposed between a part of the stand 66 and a depending finger 68 of the slide tends to move the detector 60 rearwardly into detecting position. A pin 69 carried by the slide moves in a vertical slot 70 formed in the upper arm 71 of a lever 72 movable about a fixed axis 73. The lower arm 74 of the lever is provided with a cam 75 having upper and lower cam faces 76 and 77, respectively, which cooperate with a pin or stud or the like 78 carried by the forward end of the box lever 20. 35

40 In a modification shown in Fig. 7 the detector 80 is mounted directly on the arm 81 of a lever 82 mounted and otherwise constructed similarly to lever 72. In the modification the slide 65 and attendant parts are eliminated and a spring 83 holds the lever 82 yieldingly in position to present the detector 80 to the active shuttle. 45

45 In the operation of the structure thus far described the boxes will have periods during which they are at rest with respect to the lay and other periods when they shift relatively to the lay when the latter is in its forward position. As shown in Fig. 2 the boxes are assumed to be down and at rest relatively to the lay so that the shuttle S is active. Under these conditions the forward 50 part of lever 20 will also be down to place the stud 78 at the bottom of cam face 77, and when lever 20 rises to shift the boxes, stud 78 will move upwardly along cam face 77 to cause a 55 rearward movement in the arm 74 and a corresponding forward movement of arm 71, thereby 60 moving the slide 65 and the detector 60 forwardly. 65

65 By reference to Fig. 4 this operation will be understood to begin when the lay is about in 70 its mid-position when moving forwardly. The bobbins W, W', together with their respective shuttles S and S' will start to shift before the boxes have reached a position where they could 75 interfere with and damage the prongs 61 of the 75

stationary detector and as the lay moves forwardly toward the detector the cam 75 and pin 78 will cooperate to cause forward movement of the detector. The cam can be designed to give the desired movement to keep the detector well in advance of the boxes so that as the latter shift relatively to the lay there is no opportunity for damaging the auxiliary detector.

When the lay reaches its extreme forward position the boxes are approximately half shifted at which time the stud 78 is on the high point 79 of the cam between the surfaces 76 and 77, after which continued running of the loom moves the lay rearwardly and the boxes recede from the detector as the stud 78 moves downwardly along upper cam face 76. The detector 60 and the lay therefore move rearwardly together, and at the end of the box shift the detector is back in its normal detecting position. In this way the auxiliary detector is moved out of detecting position on the forward beat of the loom when a box shift occurred, and is therefore incapable of giving indication of weft exhaustion and is also moved out of interfering position relatively to the shifting boxes.

In Fig. 4 the boxes are shown at an intermediate position in their up shift, and the dot and dash lines *a* and *b* show the forward and upward paths traversed by the bobbins *W* and *W'* respectively during such a shift. The rear position of the detector 60 is indicated in dotted lines corresponding to the dotted bobbins *W* and *W'*, while the detector is shown as having moved forwardly to the full line position when the boxes 35 and lay reach front center position.

The shifting of the boxes already mentioned renders active a shuttle which was previously inactive and this shuttle should have the weft thereof detected before it is picked to the opposite side of the loom. I make provision for this detection by the circuits indicated diagrammatically in Fig. 5. As shown therein the boxes are illustrated in their low position corresponding to Fig. 1 so that detector 51 can contact with a bobbin *W'* in the lower shuttle *S'*. A switch 90 has a pair of upper electrodes 91 and 92, respectively, and an additional pair of lower electrodes 93 and 94, respectively. A contactor 95 is arranged to connect the members of each pair, one pair at a time, so that only one pair can be electrically connected, depending upon which shuttle is active.

The contactor is mounted on the lower end of an upwardly extending rod 96 connected to the pattern lever 38 at the pivot 37 thereof. It is to be understood that before a shift of the shuttle boxes can occur an indication for the shift must be given by the pattern mechanism so that the lever 38, in order to effect the rising shift already described, must move upwardly prior to shifting of the boxes and while detector 51 is still capable of giving an indication of weft exhaustion in the lower inactive shuttle *S'*.

By referring to Fig. 5 it will be seen that when the top shuttle *S* is active the detector 41 therefore temporarily out of detecting relation with this shuttle is connected by wire 42 to electrode 93 and the latter is connected by the contactor 95 to the electrode 94. When the pattern lever 37 rises preparatory to a box shift, however, the contactor 95 will rise to the dotted line position shown in Fig. 5, thus connecting the electrodes 91 and 92, whereupon, if exhaustion be present in the inactive shuttle *S'*, current will flow from the ground over wire 53, detector 51, wire 52, elec-

trode 91, raised contactor 95, electrode 92, wire 100, solenoid 101, wire 102, source of electric power *P*, and wire 103 back to the ground. This circuit will be maintained from the time that lever 38 is raised until the boxes have risen far enough to move the prongs or detector fingers of the lower feeler away from the weft surface *W'*, but during this closure, which is sufficiently long for the purpose, energization of the solenoid 101 will move dog 104 to the left under a lever 105. By means of mechanism not shown herein but employed in a well-known continuously running shuttle changing loom movement of the dog 104 as described will effect exchange of shuttles when shuttle *S'* reaches the opposite side of the loom.

If the boxes had been raised so that cell 16 was in active position just prior to the shift, then it would be desirable to detect into the upper box, and if depletion existed in that box the following circuit could be closed: ground, wire 43, detector 41, wire 42, electrode 93, contactor 95 (which under the assumed conditions would be down), electrode 94, wire 110, solenoid 101, wire 102, source of electric power *P*, and wire 103 back to the ground. This circuit is similar to the one previously traced and when closed will energize the solenoid to effect a change in loom operation.

If detector 60 indicates exhaustion of weft on non-box-shifting beats of the loom, the following circuit is closed: ground, wire 62, prongs or fingers 61, wire 63, solenoid 101, wire 102, battery *P*, and wire 103 to ground. Excitation of the solenoid results in a change of loom operation as previously described. Magnet 115 could be energized in the same way.

Fig. 6 shows a type of loom control which can be employed with a loom which stops to effect shuttle change. Instead of the solenoid 101 I may employ a magnet or solenoid 115 mounted on the breast beam and operative to elevate a dog 116 into the path of a regularly reciprocating actuator 117, whereupon the latter will move the dog forwardly to rock a lever 118 and cause shipper handle 119 to move to stopping position. A rod 120 is shifted longitudinally when the lever 118 moves to stopping position and thereby brings about shuttle changing operations during the period in which the loom is at rest, all of this well understood.

From the description given in connection with Fig. 5 it will be seen that the detector of the inactive shuttle is rendered operative to communicate indication of weft exhaustion only on that beat of the loom when the inactive shuttle is to be returned to action by a shifting of the boxes, and since it is at this time that the auxiliary or additional detector 60 is rendered inoperative to detect, it will be seen that the detector system is capable of indicating exhaustion of weft in any shuttle which is about to be picked, whether that shuttle was previously active or inactive.

From the foregoing it will be seen that I have provided a simple detecting system employing two detector mechanisms or the like one of which includes certain feelers which are rendered operative to indicate exhaustion of weft of an inactive shuttle about to be returned to action, and the other of which provides an additional detector mechanism capable of indicating weft exhaustion in the active shuttle only and during the period that such shuttle is to remain active. It will further be seen that the auxiliary detector is rendered inoperative to give an indication of weft exhaus-

tion from either shuttle when the boxes are shifting, so that there is no opportunity for the detector mechanism on the lay to conflict with the indication given by the auxiliary detector. Also, the 5 auxiliary detector is moved out of the path of the shifting boxes to prevent breakage when the boxes are shifting and during that pick of the loom when one or the other of the feelers on the lay can indicate. Reference to Fig. 3 will show that the 10 control of the feelers on the lay, the shifting of the boxes and the movement of the auxiliary feeler into and out of operative position are all exercised through the pattern mechanism, and that the latter can be so built as to provide any desired sequence of periods of shuttle activity.

Having thus described my invention it will be seen that changes and modifications may be made therein by those skilled in the art without departing from the spirit and scope of the invention and 20 I do not wish to be limited to the details herein disclosed, but what I claim is:

1. In a weft detector system for a loom having a lay with two shifting shuttle boxes operating with two weaving shuttles, an electric weft detector on the lay above the boxes to detect into the top box when inactive, a second electric detector on the lay below the boxes to detect into the lower box when inactive, pattern mechanism to determine which shuttle box is to be active, means to 25 bring about a change in loom operation, an electric switch controlled by the pattern mechanism to render the detector corresponding to an inactive shuttle box about to become active capable of controlling the means, a third weft detector to detect 30 the active shuttle when the latter is moved forwardly by the lay, connections between the third detector and the means to actuate the latter when exhaustion occurs in the active shuttle, and means to move the third detector out of the path of 35 the boxes when the latter shift.

2. In a weft detector system for a loom having a lay with two shifting shuttle boxes operating with two weaving shuttles, an electric weft detector on the lay above the boxes to detect into the top box when inactive, a second electric detector on the lay below the boxes to detect into the lower box when inactive, pattern mechanism to determine which shuttle box is to be active, means to bring about a change in loom operation, an electric 40 switch controlled by the pattern mechanism to render the detector corresponding to an inactive shuttle box about to become active capable of controlling the means, a third detector mounted in front of the shuttle boxes and positioned 45 to detect into the actively placed box, electrical connections between the third detector and the means to actuate the latter when the third detector indicates exhaustion in an active box, and means to move the third detector out of detecting 50 position when the boxes shift with respect to the lay.

3. In a weft detector system for a loom having a lay with two shifting shuttle boxes operating with two weaving shuttles, an electric weft detector on the lay above the boxes to detect into the top box when inactive, a second electric detector on the lay below the boxes to detect into the lower box when inactive, pattern mechanism to determine which shuttle box is to be active, means to bring about a change in loom operation, an electric switch controlled by the pattern mechanism to render the detector corresponding to an inactive shuttle box about to become active capable of controlling the means, a third electric 65 detector mounted in front of the shuttle boxes 70

and positioned to detect into the actively placed shuttle box, electric connections between the third detector and the means to actuate the latter when the third detector indicates exhaustion of weft in the active shuttle box, and means controlled by the pattern mechanism to move the third detector out of detecting position when the boxes shift. 5

4. In a weft detector system for a loom having a lay with two shifting shuttle boxes operating with two weaving shuttles, an electric weft detector on the lay above the boxes to detect into the top box when inactive, a second electric detector on the lay below the boxes to detect into the lower box when inactive, pattern mechanism to determine which shuttle box is to be active, means to bring about a change in loom operation, an electric switch controlled by the pattern mechanism to render the detector corresponding to an inactive shuttle box about to become active capable of controlling the means, a third detector to cooperate with the actively placed shuttle box and control the means when exhaustion of weft occurs in the actively placed box, and means to move the third detector out of detecting position when the boxes shift. 10 15 20

5. In a weft detector system for a loom having a lay with two shifting shuttle boxes operating with two weaving shuttles, an electric weft detector on the lay above the boxes to detect into the top box when inactive, a second electric detector on the lay below the boxes to detect into the lower box when inactive, pattern mechanism to determine which shuttle box is to be active, means to bring about a change in loom operation, an electric switch controlled by the pattern mechanism to render the detector corresponding to an inactive shuttle box about to become active capable of controlling the means, a third detector to cooperate with the actively placed shuttle box and control the means when exhaustion of weft occurs in the actively placed box, and means to move the third detector out of detecting position when the boxes shift. 30 35 40 45

6. In a weft detecting system for a loom having a lay supporting two shuttle boxes to cooperate with two weaving shuttles, pattern mechanism to determine which shuttle box shall be in active position, a pair of weft detecting mechanisms secured to the lay, one for each shuttle box, to detect the condition of weft in the inactive shuttle, means controlled by the pattern mechanism to render operative the detecting mechanism corresponding to the inactive shuttle just prior to the return of said inactive shuttle to active position, a third detector to detect the condition of weft in an actively placed shuttle box, and means controlled by the pattern mechanism to move the last named detector out of detecting position when the boxes shift, whereby each of the weaving shuttles is detected as to the condition of weft therein within one beat of the loom of the time the shuttle is to become active, whether the shuttle moves from inactive to active position or remains active. 50 55 60 65 70

7. In a weft detecting system for a loom having a lay having two shuttle boxes operating with two shuttles each movable to active and inactive positions, a pair of weft detectors secured to the lay each to detect into one of the shuttle boxes 75

when inactive, pattern mechanism to render the detector corresponding to an inactive shuttle capable of controlling the loom just prior to the return of an inactive exhausted shuttle to active position, a third detector mounted in front of the shuttle boxes to detect into the actively placed box and effective when indicating exhaustion of weft in the active shuttle to control loom operation, and means controlled by the pattern mechanism to move the third detector out of the path of the shifting boxes when the latter shift relatively to the lay, whereby each shuttle is detected immediately before being picked whether previously active or inactive.

15. 8. In a weft detecting system for a loom having a lay supporting two shuttle boxes operating with two shuttles each movable to active and inactive positions, pattern mechanism to determine which shuttle box shall be active, weft detecting means to detect the condition of weft in an inactive shuttle, means controlled by the pattern mechanism to render the detector mechanism operative to control the loom just prior to the return of the previously inactive depleted shuttle to action, additional weft detecting mechanism to detect the condition of weft in the active shuttle box and effective to control loom operation, and mechanism controlled by the pattern mechanism to move the additional weft detector out of the path of the boxes when the latter shift relatively to the lay, whereby each shuttle is detected within one beat of the loom from the time that it is to be active whether previously active or inactive.

35. 9. In a loom operating with two weaving shuttles and having shifting shuttle boxes movable relatively to a lay to render either shuttle active, pattern mechanism to determine which shuttle box shall be in active position, a weft detector secured to the lay in vertical alignment with the boxes to detect the condition of weft in one of the weaving shuttles due to shifting action of the boxes relatively to the lay when said shuttle is moved to inactive position, a second weft detector mounted in front of the boxes to detect the condition of an active shuttle, connections between the pattern mechanism and said second weft detector to render the latter incapable of detecting weft when the shuttle boxes are shifting, and means to control the operation of the loom to be operatively related to both detectors and effective to change the operation of the loom when either detector indicates exhaustion of weft whereby the said one of the weaving shuttles is detected im-

mediately before being picked whether previously active or inactive.

10. In a weft detecting system for a loom operating with shifting shuttle boxes to render either of two weaving shuttles alternately active and inactive, pattern mechanism to determine which shuttle box shall be in active position, a detector positioned to detect the condition of weft in one of the weaving shuttles when the latter is in inactive position due to shifting of the boxes, a 10 second weft detector adjacent the boxes to detect the condition of weft in either weaving shuttle when active, connections between the pattern mechanism and said second weft detector to render the latter incapable of detecting weft when 15 the shuttle boxes are shifting, and loom controlling means to be operatively related to both detectors and capable of bringing about a change in loom operation when either detector indicates weft exhaustion whereby the said one of the 20 weaving shuttles is detected immediately before being picked whether previously active or inactive.

11. In a weft detecting system for a loom operating with shifting shuttle boxes to render a weaving shuttle alternately active and inactive, a 25 detector for the weaving shuttle when the latter has been rendered inactive by a shifting of the boxes, a second detector for the weaving shuttle when the latter remains in action due to non-shifting of the boxes, means to render said detectors alternately operative with respect to the weaving shuttle, said means rendering the first detector operative to detect the weaving shuttle when the latter becomes inactive and simultaneously rendering the second detector inoperative, 30 said means rendering the first detector inoperative when the weaving shuttle returns to action, and means to bring about change in loom operation when either detector indicates exhaustion of weft.

12. In a weft detecting system for a loom operating with shifting shuttle boxes to render one or the other of two weaving shuttles either active or inactive, a lay to move the boxes backwardly and forwardly, weft detectors on the lay one over and the other under the boxes, each detector to cooperate with the corresponding shuttle box when the latter is inactive, a third weft detector mounted in front of the shuttle boxes to detect the condition of weft in the actively placed shuttle box, and means brought into action when the shuttle boxes shift relatively to the lay to move the third detector out of the path of the shifting boxes.

LEWIS S. VOSE. 55
